UNITED STATES PATENT OFFICE.

LORN CAMPBELL, JR., OF MINNEAPOLIS, MINNESOTA.

ACETYLENE-GAS GENERATOR.

Application filed April 27, 1920. Serial No. 376,940.

To all whom it may concern:

Be it known that I, LORN CAMPBELL, Jr., a citizen of the United States, residing at Minneapolis, in the county of Hennepin and State of Minnesota, have invented a new and useful Acetylene-Gas Generator, of which the following is a specification.

My invention relates to improvements in acetylene gas generators.

10 Its object is to provide a simple, durable and compact gas generator comprising a tank with carbide feeding mechanism therein, a bracket on said tank adapted to carry a motor for driving said mechanism, controlling mechanism for the motor and pressure operated actuating means for said controlling mechanism, said bracket being formed with a passageway leading from said tank to said actuating mechanism.

20 Another object is to provide a device of this kind having a driving shaft entering the tank, a bracket functioning, as above, and supplied with a stuffing box for said shaft.

25 With the foregoing and other objects in view, which will appear in the following description, the invention resides in the novel combination and arrangement of parts and in the details of construction hereinafter described and claimed.

30 In the drawings Fig. 1 is a view, partly in section, illustrating a device embodying my invention; Fig. 2 is a perspective view in detail of the motor supporting bracket; Fig. 3 is a sectional view taken on the line 3—3 of Fig. 1 and Fig. 4 is a sectional view taken on the line 4—4 of Fig. 3 and illustrating particularly the motor, supporting bracket therefor and actuating means for 40 the motor controlling mechanism.

Referring to the drawings, I have used the reference numeral 10 to indicate a tank having a removable cover 11 therefor. Said tank is supplied with a gas outlet 12 and a water inlet 13. A hopper 14, secured to the cover 11, opens above a feeding platform 15 suspended by rods 16 attached to said hopper. An opening 17 in said cover, normally closed by a plug 18, provides for the introduction of carbide to the hopper 14. A feeding shaft 19 revolvable at its lower end in said platform and passing through an opening 20 in the cover 11 of the tank, is supplied at its lower end with an agitator 21 fixed against rotation with respect thereto. Said shaft 19 is rotated, as will

hereinafter appear, to feed carbide from the platform 15 into water beneath said platform. I supply a bracket A designed to be attached to the cover 11 of the generating tank, said bracket being adapted to revolvably receive the feeding shaft 19, close the opening 20 in the cover 11, support a motor for turning said shaft, also the controlling mechanism for the motor and the pressure operated actuating means for said controlling mechanism, said bracket being further adapted to furnish means of communication between the interior of the tank and said actuating means. This bracket comprises a body portion 22 having flanges 23 and 24 at the extremities thereof, said body portion being formed with a passageway 25 extending therethrough. The flange 23 has a reduced portion 23^a formed with a bore 26 therein to receive the feeding shaft 19. A gland 27 threaded in an enlargement 28 of the bore 26 retains stuffing material 29 therein and forms a pressure tight joint between said flange 23 and the shaft 19. The reduced portion 23^a of the flange 23 is threaded in the opening 20 or otherwise secured therein, so as to draw the rim 23^b of the flange 23 against a gasket 30 interposed between said flange and cover. The upper flange 24 of the bracket A is offset from the lower flange 23 sufficiently to clear the feeding shaft 19. A motor frame B, consisting of upper and lower plates 31 and 32 spaced apart by posts 33, is secured by means of screws 34 to the upper flange 24. Interposed between said lower plate 32 and flange 24 is a disc or diaphragm 35, spaced apart from said flange and plate by means of annular shims 36. Pressure from within the tank 10, communicated to the diaphragm 35 through the passageway 25 in the bracket, lifts the diaphragm, which action is employed to regulate the driving motor. This motor may be of any suitable type, electric, weight or water driven or spring propelled as illustrated herein, the connection between the motor and shaft 19 being accomplished in any convenient manner. The motor illustrated comprises a winding shaft 37, journaled near its upper end in the plate 31 and at its lower end in a socket 38 in the driving shaft 19. A spring supporting plate 39 fixed to said winding shaft 37 carries a spiral spring 40, which is secured at its inner end to said shaft and anchored at its outer end to a post 33 in the motor frame. This plate

carries a dog 41 engaging a ratchet wheel 42 on the feeding shaft 19. A large spur gear 43 on said shaft 19 meshes with a small gear 44 on an idler shaft 45 carrying a large gear 46 meshing with a small gear 47 on a governor shaft 48. A sleeve 49 on the governor shaft 48 is formed with an annular brake member 50, which is depressed upon the spreading of governor arms 51 attached 10 to said shaft 48 and sleeve 49. An adjustable abutment 52 for said brake member 50 is carried in the free end of an oscillatory arm 53 pivotally attached to the plate 32 of the motor frame. This arm 53 lies in a 15 guide 54 formed on a rest 55, said rest being seated upon the diaphragm 35 and passing through an opening 36^a in the lower plate 32 of the motor frame. To provide for the maintenance of various pressures within the 20 tank, I employ a coiled compression spring 56, the lower end thereof encircling a lug 57 on the arm 53 and the upper end encircling a lug 58 on a head-piece 59. A set screw 60 threaded in the upper plate 31 is 25 seated in a depression 61 in said head piece. This spring and adjusting screw provide for the application of various yielding pressures against the arm 53 and furnishes conveniently adjustable means, whereby desired 30 pressures of gas may be maintained within the tank 10.

One of the principal advantages of my invention resides in the employment of a bracket to support a motor, the controlling 35 mechanism therefor and the actuating means for said controlling mechanism, said bracket serving further to seal the opening in the tank for the driving shaft and furnish means of communication between the tank 40 and actuating means for the motor governing mechanism.

Changes in the specific form of my invention, as herein disclosed, may be made 45 within the scope of what is claimed without departing from the spirit of my invention.

Having described my invention, what I

claim as new and desire to protect by Letters Patent is:

1. In a device of the class described, the combination with a generating tank of a 50 unitary carbide feeding mechanism for said tank having communication therewith through a single opening therein, said mechanism including a motor, a feeding shaft operated thereby and reaching into the 55 tank through said opening, a diaphragm, motor controlling means actuated by the latter, and a hollow bracket upon which said members are mounted, said bracket supplying the sole anchorage to the tank for said 60 mechanism and serving to close the opening in said tank, also serving as a conduit between the tank and diaphragm and as a bearing for said shaft at its point of entry 65 into the tank.

2. In a device of the class described, a generating tank, and carbide feeding mechanism therefor including a rotary feeding shaft entering said tank through an opening 70 therein, a bracket including a body portion, a flange at the base thereof receiving said shaft, and a second flange at the outer end of the body portion, said first mentioned flange being attached to the tank and serving 75 to close the opening therein, a packing gland for the shaft applied to the base flange from the outer side thereof, said body portion being formed so that said second flange 80 clears the feeding shaft and gland therefor, a diaphragm mounted on said second flange, said body portion of said bracket being formed with a passage-way therein communicating with the tank and leading to 85 said diaphragm, a motor frame also mounted on said second flange, a motor to drive the feeding shaft and motor controlling mechanism both carried by the frame, said mechanism being actuated by said diaphragm.

In testimony whereof, I have signed my name to this specification.

LORN CAMPBELL, JR.
